APRON FOR CARRYING ARTICLES

Matilda C. Lipscomb, Little Rock, Ark.

Application May 7, 1957, Serial No. 657,660

7 Claims. (Cl. 2—48)

This invention relates to aprons which serve the usual function of protecting clothing from dust and spillage, but which are also useful as carrying devices.

The aprons of this invention are intended for use by anyone engaged in transporting a number of variously located small objects from one place to another, either from a number of different places to one central point or vice versa.

In a household these small objects may consist of housecleaning equipment, children's toys, ashtrays, books, laundry, etc. On a farm they may be potatoes, eggs, apples, flower bulbs, gardening tools, or other articles. In industry, for which these aprons are especially intended, it is difficult to enumerate all of the possible uses for these carrying aprons in various types of manufacturing establishments, in retail stores, and even more specifically in the jobbing trade, where literally thousands of items are bought in large quantities and systematically shelved in order that they may be subsequently reassembled in smaller quantities of various combinations for individual retailers.

In wholesale warehouses, the persons engaged in these reassembling operations are called "order fillers" or "pickers." It is their job to select from the shelves assigned to them the merchandise called for by each order and to transport it from its location on the shelf to the basket, box or buggy, into which the entire order is being assembled. In many cases they are also required to price each item they pick.

On slow days, or whenever time permits, these order fillers are engaged in shelving, which consists of keeping their shelves dusted, in order, and restocked with merchandise from full cases. The carrying apron of this invention functions just as well in shelving as it does in picking. Since the apron can be worn down when the picker is not shelving or filling an order, it serves as a protective cover for the front of her clothes. When she is shelving or filling orders, the apron not only protects her clothes, but serves as a working tool to enable her to do her job faster, with fewer steps, more easily, more comfortably and with less danger of dropping and breakage.

It is an object of this invention to provide a carrying apron, of the character indicated, which is convenient to use so that work can be done more efficiently and with less fatigue. Another object is to provide such an apron constructed so that it is easily put on, and with no adjustments other than the ties which are joined in a bow knot as with conventional aprons.

Other features of the invention relate to the simplicity of construction of the apron and to its attractive appearance which improves morale.

2

The apron of this invention is constructed to provide even distribution of the weight load for shoulders, hips and arm; and it leaves the wearer with both hands free for holding packages or pencil and paper used in connection with the filling of orders.

Other objects, features and advantages of the invention will appear or be pointed out as the description proceeds.

In the drawing, forming a part hereof, in which like reference characters indicate corresponding parts in all the views:

Figure 1 is a view showing the different parts used to make an apron embodying this invention;

Figure 2 is a perspective view of the completed apron with the ties threaded through corner loop holes in the apron preparatory to putting the apron on;

Figure 3 is a perspective view showing the manner in which the apron is worn while being used for carrying articles; and

Figure 4 is a perspective view showing the way in which the shoulder straps extend down the back of the wearer and showing how easily the apron can be adjusted to the size of the individual wearer by pulling the apron in at the back with the ties.

The parts from which the apron is made are shown in Figure 1. These include a skirt portion 10 having a rounded bottom edge 12 and a center reinforcing patch 14. There are three intermediate loops 16 each of which is connected at its outer end to the edge portion of the apron; and each of which is connected at its inner end with the part of the apron skirt which is covered by the reinforcing patch 14. There is an end loop 18 located on one side of the skirt and this end loop has both of its ends connected to the edge portion of the apron skirt 10 at regions spaced along the length of the edge portion. There is a similar end loop 18 on the other side of the apron skirt.

The skirt 10 can be made without the reinforcing patch 14, but this patch serves as a bottom under the pocket when the apron is being used to carry articles and it greatly increases the useful life of the apron by improving the wearing qualities. In order to improve the appearance of the garment, the apron preferably has a binding 20 extending around the edge and of contrasting color with the material from which the skirt is made.

The apron includes also an upper portion 22 which extends upwardly from the waist and which preferably has pockets 24 useful for holding pencils and order blanks or other papers needed in connection with the work being done. The upper portion 22 is of increased width toward its lower end so as to extend entirely across the front of the wearer and at least as far as the wearer's hips. There are corner loop eyes or holes 26 provided on the upper portion 22 just above the wearer's hips, for receiving ties which hold the apron in place, as will be explained more fully in connection with the other views.

The apron illustrated is designed more especially for women and it has the upper edge of the skirt 10 considerably wider than the bottom edge of the upper portion 22 to which the skirt connects. This extra width permits the skirt to be connected to the upper portion 22 with gathers 28 (Figure 2) which give the skirt greater fullness and improve its appearance and carrying

capacity. There are darts 30 at the lower part of the upper portion 22 for providing fullness over the bosom of the wearer. This prevents a direct downward pull and uncomfortable pressure against the breasts of women workers, and it distributes the downward pull toward both sides of the apron.

Shoulder straps 32, preferably of double thickness, are attached to the top of the upper portion 22; and these shoulder straps are wide enough to distribute the weight of the apron and its contents over a wide area for greater comfort. A yoke 34 is attached to the other ends of the shoulder straps 32, and this yoke holds the back of the shoulder straps in place, and eliminates the need for crossing the straps in back each time the apron is put on. The apron has ties 36 connected to the yoke 34. These ties are passed through the loop holes 26 and are preferably knotted at their ends. The knots, indicated by the reference characters 38, prevent the ties 36 from pulling out of the loop holes 26.

In Figure 2 the apron 10 is shown hanging down in the position which it occupies when not being used for carrying articles. Figures 3 and 4 show the way in which the apron is used as a carrying device.

After the apron is slipped on, the ties 36 are pulled together behind the wearer and tied in a bow knot 42, as shown in Figure 4. The pull of the ties 36 on the corner loop holes 26 holds the apron as tight as may be desired around the waist of the wearer so that much of the weight of the articles carried in the apron is supported from the hips. The downward pull of the ties 36 on the shoulder straps makes it unnecessary to provide adjustment of the shoulder straps for persons of different height. Differences in the size of the person wearing the apron affect the extent to which the shoulder straps reach downwardly behind the wearer and affect the extent to which the apron wraps around the wearer; but all of the adjustment necessary is taken care of by pulling in on the ties 36.

Only four of the five loops are generally used. A right handed person inserts her left arm through one of the loops 18 and through the three intermediate loops 16 as shown in Figure 3. The other side loop 18 is not used. A left handed person will insert her right arm through the free loop in Figure 3, and through the three intermediate loops 16, leaving the other side loop 18 unused.

The three intermediate or bottom loops 16 hold up the lower end of the apron to form the carrying pocket, whereas the side loop 18 forms an end on the pocket to prevent articles from spilling out at the end.

By having the bottom of the skirt rounded, the load is evenly distributed among the intermediate loops 16. If the bottom of the apron were straight, instead of rounded, a disproportionate part of the load would be carried by the middle loop, thus imposing excessive strain on one part of the forearm.

The side of the pocket which is being touched by the right hand of the wearer in Figure 3 does not have to be supported by a loop because this end of the pocket is held up by the fact that the wearer's hand is held out from her body and the distance prevents the free edge portion of the skirt from sagging.

From Figure 3 it will be apparent that the skirt 10 provides a deep and easily accessible pocket for carrying articles; and the pocket is at a convenient position for inserting and removing articles as necessary during the course of the work. Although the worker's left arm is occupied in Figure 3, her hand is free to the extent that she can hold a board on which orders may be clipped while making notes on the orders with a pencil held in the other hand. The hand of the arm which passes through the loops is sufficiently free for numerous other operations which may require two hands.

In the preferred construction of the apron, the loops 16 and 18 are on the back of the skirt. This is advan-

tageous because it locates the loops out of the way when the skirt 10 is hanging down, as shown in Figure 2. If the loops are on the front of the skirt the appearance is impaired, they are less convenient to use, and they sometimes catch on the edges of shelving or other projecting articles against which the skirt may brush when passing.

The apron illustrated can be used by either men or women. Modifications of the illustrated construction for use by men only are made without the gathers 28 (Figure 2) and without the darts 30. This simplifies the construction somewhat, but for a skirt of equal length, the carrying capacity is somewhat decreased.

Other changes and modifications can be made, and some features can be used in different combinations, without departing from the invention as defined in the claims.

What is claimed is:

1. A carrying apron including a skirt portion with a bottom edge and side edges, loops at spaced locations 20 along the edges of the skirt and extending transversely of said edges and in position to receive an arm of the wearer of the apron to support the lower part of the skirt portion and thereby form a trough for holding articles to be carried, one of the loops being connected to the skirt portion adjacent to the bottom edge, and another of the loops being connected to the apron at a location along one side edge of the skirt portion so as to hold up a part of the skirt that forms an end for the trough.

2. The carrying apron described in claim 1 and in 30 which there are side loops connected to the apron along opposite side edges of the apron for receiving the arm of a right-handed or left-handed wearer to provide an end for the trough at either the right or left side of the apron, depending upon which arm is used by the wearer 35 to support the apron.

3. The carrying apron described in claim 1 and in which some of the loops are along the bottom edge of the skirt and others along a side edge, and the loops are strips attached to the skirt portion at their opposite ends 40 and in positions to make the strips lie flat against the skirt portion when not in use.

4. The carrying apron described in claim 3 and in which each of the loops at the bottom edge of the skirt portion has one end connected near the edge of the skirt portion and the other end connected to the skirt portion 45 at a substantial distance inward from the edge, and in which the side loop has both ends connected to the skirt portion near the edge thereof, and the loops are attached in position to lie against the underside of the skirt portion and the skirt portion has a reinforcing ply at its mid portion extending outwardly as far as the locations at which the bottom loops connect with the skirt portion, and a top binding at the upper end of the skirt portion to which the skirt portion is connected with gathered 55 regions of the skirt portion permanently connected to the top binding to provide extra fullness, and ties with means connecting them to the upper part of the skirt portion at both sides of the skirt portion for extending around the back of a person wearing the apron.

5. The carrying apron described in claim 1 and in which the loops are located on the side of the apron facing the wearer when the skirt portion is hanging down and not in use for carrying, whereby the loops are protected from catching on the edges of shelving or other 60 projecting articles against which the skirt portion may brush when passing.

6. The carrying apron described in claim 1 and in which the apron has a top binding to which the upper end of the skirt portions is permanently connected and a bib extending upwardly from the skirt portions, and shoulder straps at the upper end of the bib, the bib having darts at its lower end to give fullness to the bib and to shift the direct downward pull of the apron toward 65 the sides of the bib.

7. An apron including a skirt that hangs down straight from a wearer's waist to a bottom edge of the apron, a plurality of loops at spaced locations along the bottom edge of the skirt and extending transversely thereof, each of the loops being large enough to fit freely over one arm of the wearer of the apron when the apron skirt is to be used as a carrier, the loops being in position to receive the wearer's arm when said arm is bent inwardly in front of the wearer, and the loops being close enough to the apron throughout their entire extent to hold the skirt folded upwardly into a trough when the wearer's arm is

10 through the loops and the apron is being used as a carrier.
